His Attorney.

UNITED STATES PATENT OFFICE

CLYDE E. STEWART, OF DREXEL HILL, PENNSYLVANIA, ASSIGNOR TO GENERAL ELECTRIC COMPANY, A CORPORATION OF NEW YORK

SUPERVISORY SYSTEM

Application filed September 19, 1928. Serial No. 306,941.

My invention relates to remote supervisory systems, and more particularly to means for remotely supervising the operation of power switches or other movable devices.

5 It has for its purpose to provide a method and means which are particularly adapted for use in connection with small power installations, or installations in which switches are distributed about at different locations, 10 either separate switches, or small groups of switches being located in each of the different locations, whereby the operation of said switches may be supervised from a central station.

15 Briefly, in carrying my invention into effect, means are provided in connection with each switch whereby a common indicating device at the central station is operated in response to actuation, automatic, or otherwise, 20 of any of the remote switches, together with means whereby the operator at the central station by sending predetermined signals, as for example, current impulses in code combination, to each of the switches may produce 25 additional actuation of the common indicating device at the central station only when a signal corresponding to the actuated switch has been transmitted from the central station. In this manner the operator at the 30 central station may determine which of the remote switches operated.

A further purpose of the invention is to provide means whereby when two or more switches have been operated simultaneously 35 and the operator has, by the means indicated, determined that a certain one of two or more switches has operated, he may afterwards determine which of the other switches has operated, notwithstanding that the indication is received upon a common indicating device in the central station.

Another purpose of the invention is to provide means whereby the above results may 45 be accomplished by the use of a single line, or pair of wires, extending from the central station to the locality of each of the remote switches.

Still another purpose of the invention is 50 to provide means whereby the results indi-

cated may be accomplished with a minimum of operations by the operator.

Another purpose of the invention is to provide means which are relatively inexpensive to install and maintain and which are simple 55 in operation.

The novel features which I believe to be characteristic of my invention are set forth with particularity in the appended claims. My invention itself, however, both as to its 60 organization and method of operation, together with further objects and advantages thereof, may best be understood by reference to the following description taken in connection with the accompanying drawing in which 65 the single figure represents an embodiment of my invention.

Referring to the drawing I have represented at A a central station from which a pair of conductors 1 extend to the locality, 70 or localities, of a plurality of movable devices such, for example, as that which I have indicated as a switch 2. Associated with each of the movable devices or switches 2 is an apparatus which I have designated B on the 75 drawing comprising a plurality of switches 3, 3' and 3'' which are mechanically connected, or interlocked, with the switch 2, and an induction coil 4 which is controlled thereby. The switch 2 is shown in its normal, or 80 closed, position and is adapted, upon actuation, to its off-normal, or open, position to open the switch 3'' and to close the switch 3 and 3' for purposes presently to be described.

The induction device 4 has a high frequency secondary winding 6 which is connected through a condenser to the line 1. This device is also provided with a primary or actuating winding 7 and an armature 8. By 90 actuation of the switch 2 to its off-normal position a circuit is completed which extends from the negative side of a source of potential 9 through switch 3, normally closed contacts of relay 10, actuating winding 7 of the 95 device 4, and stationary contact and armature 8 to the positive side of the source of potential 9. This circuit comprises a buzzer circuit for the coil 7 which, by successively operating the armature 8, causes the induc- 100

tion coil 4 to supply high frequency current to the line 1 in a manner well known in the art. Also, upon opening of the switch 2 a circuit is completed extending from one side of a source of potential 11 through the switch 3' and actuating winding of relay 10 to the opposite side of the source 11, thereby causing energization of the relay 10. This relay may be of any suitable type which is adapted to open its contacts only after its actuating winding has been energized for a predetermined interval. When the contacts of this relay are opened the buzzer or actuating circuit of the induction coil is interrupted and the supply of high frequency current to the line is discontinued.

It will thus be seen that upon actuation of any switch 2 to its off normal position a high frequency current is supplied to the line 1 for a predetermined interval, as determined by the adjustment of the time delay device which is associated with relay 10.

Located in the central station A and connected across the line 1 is a suitable alternating current responsive indicating device 12 such, for example, as an induction howler or loud speaker. Of course, any visual indicating means may be used as well. Thus, upon operation of switch 2 this howler will be caused to respond informing the operator at that station that one or more of the remote switches has been actuated to its off-normal position. Located also in the central station A are a plurality of signal sending, or impulse producing devices, which are represented as disks 13, 13', 13''. These devices are of well known construction and are provided with an actuating spring, not shown, and mechanism such that when the spring is wound by the operator the disks revolve through a complete revolution to produce, in cooperation with relays 16 and 17, current impulses in the circuit 1 in suitable predetermined code combination. Line 1 at the central station extends through the contacts of relays 16 and 17 and a pair of choke coils 5 to a source of direct current potential 18. The relay 17 is of a type such that in one position it connects the source 18 to the line 50 in a manner to produce current of a certain polarity in the line and, upon actuation to the opposite position, it reverses the polarity of that current.

Each of the disks 13 is provided with a contact which is normally positioned in a notch in the rim of the disk such that it is out of engagement with the disk. Upon initiation of the rotation of the disk 13 the contact 19 engages the disk and remains in engagement therewith throughout the complete revolution and until the disk 13 returns to its normal position. The disk 13 is provided with projections upon its periphery such that when the contact 19 engages these projections it is actuated into engagement

with a second contact 20. The connections with the relays 16 and 17 are such that when the contact 19 engages the disk 13 the actuating winding of the relay 16 is energized and this relay closes its contacts. This circuit extends from the negative side of the source of potential 21 through contact 19, disk 13, and actuating winding of relay 16 to the opposite side of the source of potential 21. When the contact 19 engages the contact 20 a circuit is completed which extends from the negative side of the source of potential 21 through contacts 19 and 20, and actuating winding of the relay 17 to the opposite side of the source of potential 21. Thus, during a revolution of the disk the relay 16 is continuously energized and the relay 17 is alternately energized and deenergized in accordance with the code combination determined by the projections on the disk 13.

In this way current impulses of reverse polarity are transmitted through the line 1. For illustrative purposes, I have shown the disk 13 provided with an adjustable plate 22 such that these current impulses may be divided into a pair of groups, each group having a predetermined number of impulses of reverse polarity. The disk 13' is so adjusted by means of the plate 22' that a single group of impulses having any desired predetermined number of reversals may be transmitted. The disk 13'' is provided with two plates 22'' so adjusted that the transmitted impulses are divided into three groups.

Also comprised in the apparatus B, which is associated with each of the switches 2, is a selector switch 23 having an actuating winding 24 which is connected through a condenser to the line 1. This switch may be of any suitable construction but is of a type such that upon receipt of current impulses in code combination corresponding to the particular switch 2 its armature will engage a certain contact, and in response to a different code combination of impulses its armature will engage a different contact, or after actuation, will return to its initial position without engaging any contact. Preferably this switch is of a type shown in Patent No. 1,343,256, J. C. Field, issued July 15, 1920. Upon receipt from the line 1 by the selector 23 of a number of impulses in code combination corresponding to the particular switch which has been actuated, this selector will engage its first contact and thereby complete a circuit which extends from the negative side of the source of potential 9 through switch 3 which is now closed, due to actuation of the switch to its off-normal position, armature 8 and first contact of selector 23, contacts of relay 25, actuating winding of the induction coil 4, stationary contact and armature 8 to the positive side of the source of potential 9.

Thus, it will be apparent that the contacts

of the selector 23 which has been actuated, as described, produce a short circuit about the contacts of relay 10 and again energize the induction coil, notwithstanding that operation of that device in response to operation of the switch 2, has been interrupted by the relay 10. High frequency current will then be again supplied to the line. This circuit will be completed only in the apparatus B which is associated with a switch 2 which has been actuated to its off-normal position. The operator of the station A, knowing the code combination which he has transmitted and which has caused operation of the indicating device 12, will then be informed as to which of the remote switches has operated.

Thus, upon operation of the device 12 in response to operation of any remote switch, the operator will proceed to operate the devices 13 at the central station until he receives an additional response from the device 12. This additional response will inform him that the switch corresponding to the code number which he last transmitted is the one that operated.

To obviate the necessity of the operator's dialing the number of every switch, the different remote switches are divided into groups, each group having a group number. The group divisions I have indicated by rectangles 26, 27 having conductors 28, 29 respectively leading therein, as to the different devices B. Each of the individual selector switches 23 in each group is adjusted to respond to the code combination of impulses corresponding to the group number, and also to a different combination of impulses corresponding to the individual number of the switch 2 with which the particular selector switch 23 is associated.

Thus, for example, let us suppose that there are 16 remote switches divided into groups of four. Upon receiving an indication from the device 12 at the central station the operator will proceed to dial the group numbers of the different switches. Let us suppose that he dials three group numbers and receives no response from the device 12. He is then informed that none of the switches

in the groups, the group numbers of which he has dialed, has been actuated. He then dials a fourth group number and receives a response from the device 12 indicating that one of the switches in this group has been actuated. He will then proceed to dial the individual numbers of the different switches in this last group. Upon dialing the first three individual numbers he receives no response from the device 12. Upon dialing the fourth individual number he receives a response from the device 12 informing him that it was the last of the sixteen switches which operated.

When the operator dials a group number and receives a response from device 12, he

does not know how many switches in the group have operated. Also after he dials an individual number in the group and receives a response from device 12 he does not know whether any other switch, whose individual number he has not dialed, has operated. In accordance with a feature of my invention, I provide an arrangement whereby the operator after he has dialed an individual number in a group and has received a response from device 12, thereby indicating the operation of the corresponding switch in the group, may determine whether or not any other switch in the group has operated without dialing the individual numbers of all the other switches in the group. This result is accomplished by providing an arrangement whereby induction device 4 of an operated switch may be prevented from effecting the operation of the device 12 in response to the code of impulses which normally effects the operation thereof. In the particular embodiment of my invention shown in the drawing, this result may be accomplished by dialing in any suitable manner, a code of impulses which will cause the selective relay associated with a particular operated switch to be operated to its third contact position instead of its first contact position, thereby energizing through an obvious circuit the left-hand winding of relay 25. This relay is of the position type such that upon energization of this winding its armature is actuated from the position shown in the drawing to the opposite position. The actuating winding 7 of the induction coil will then be deenergized. Operation of the other switches may then be ascertained as described. With the relay 25 in the position opposite to that shown in the drawing, when the switch 2 is returned to its normal position, either manually or automatically, the right-hand winding of this relay will be energized through a circuit including the switch 3". This winding of the relay will return the armature to the position shown in the drawing, and the device is then in readiness for an additional operation.

As a specific example of the use of the code numbers in connection with the operation of my device, when a selector switch 23 of the type described in the previously mentioned patent is employed, let us assume again that there are 16 switches divided into groups of four. The adjustment of the different selector switches will then be such that upon dialing of 17 impulses in a single group, as by a disk adjusted as shown at 13', all of the switches 23 will be operated to close their first contacts. If any remote switch is then in its off-normal position, a response by the device 12 at the station A will be had. Thus the operator after having determined that a particular switch has been actuated to its

off-normal position may advantageously dial the single group code number to determine whether any other switch in any group has operated. The code numbers of the different groups will each include two sets of impulses, the sum of which will be 17, as for example, 7-10; 6-11; 5-12; 4-13, etc. Thus, upon dialing of any of these numbers, as by means of a disk adjusted to transmit two groups of impulses, as for example, disk 13, every switch in the group to which that number pertains responds to close its first contacts, whereas the switches in other groups will not close their contacts but instead will return, after actuation to their initial position. If any switch in the groups, the group number of which has been dialed, is in its off-normal position a response will be had from the device 12 at the station A. The individual numbers of the switches in each group will comprise three sets of impulses of which the first set will have the same number as the first set of the group number, and the sum of the impulses in the last two sets of the individual number will equal the number in the second set of the group number; for example, in the group 7-10 the individual numbers will be 7-2-8; 7-3-7, 7-4-6 and 7-3-7. Thus after the group in which a switch has operated is located the operator will dial the individual numbers until the individual switch is located. As pointed out above, after the operator has determined that a particular switch in a group has operated, the operator dials a code of impulses which causes the selective relay, associated with the operated switch, to cause the corresponding relay 25 to occupy the position opposite to that shown in the drawing. Therefore when the selective relay 23 of the operated switch is subsequently moved to its first position in response to the group code, the selective relay does not effect the connection of the associated generator 11 to the line 1. The operator then dials the group number and if he receives a response from device 12 he knows that some other switch in the group has operated. He then dials the other individual code numbers of the switches in the group until he receives another response from the device 12. He repeats this cycle of operation until the device 12 does not operate in response to the dialing of the group number.

While in the case shown in the drawing and as described, I have represented an induction coil and selector switch associated with each of the remote switches, it will of course be understood that since each of the switches 23 is adapted to close any one of a plurality of contacts in response to different code impulses, the system may readily be modified such that a single switch 23 and induction coil 4 may be associated with two

or more of the switches 2 without departing from my invention.

While I have shown a single embodiment of my invention, it will of course be understood that I do not wish to be limited thereto since many modifications, both in the circuit arrangement and in the instrumentalities employed, may be made without departing from the spirit and scope of my invention as set forth in the appended claims.

What I claim as new and desire to secure by Letters Patent of the United States, is:

1. In a supervisory system, a line, a plurality of devices, means associated with each device for supplying high frequency current to said line in response to the actuation of the device to a certain position, timing means associated with each device and controlled thereby for interrupting the supply of high frequency current to the line after the device has been in said certain position for a predetermined time, and means associated with each device and responsive to direct current impulses received from the line for causing additional high frequency current to be supplied to said line when the device is in said certain position.

2. In a supervisory system, a line, a plurality of devices, means associated with each device for supplying high frequency current to said line in response to the actuation of the device to a certain position, timing means associated with each device and controlled thereby for interrupting the supply of high frequency current to the line after the device has been in said certain position for a predetermined time, and means associated with each device and responsive to direct current impulses received from the line for additionally actuating the associated high frequency current supplying means without operating the device when the device is in said certain position.

3. In combination, a central station, a remote station including a plurality of devices, each of said devices having a normal position and an off-normal position, a signal device in the central station common to all of the remote devices, means responsive to actuation of each of said remote devices from the normal position to an off-normal position for actuating said signal device for a predetermined time interval after the actuation of the remote device, signal sending means at the central station, and means at the remote station responsive to a predetermined signal received from said central station for actuating said signal device subsequent to said time interval when said remote device is in its off-normal position.

4. In combination, a central station, a remote station including a plurality of devices, a line joining said stations, means responsive to actuation of any of said devices for supplying high frequency current to said line,

signal means in the central station responsive to said high frequency current, timing means controlled by a device for interrupting the operation of said current supply means, code-sending means in the central station, and 5 means responsive to the position of an actuated device and to a predetermined code received from the central station for causing said current supply means to supply current to said line to actuate said signal subsequent to operation of said time-controlled means.

10 5. In combination, a central station, a plurality of remote devices arranged in groups, a signal in said central station common to all 15 of the remote devices, means responsive to actuation of any of said devices to a predetermined position for effecting actuation of said signal for a predetermined time, code sending means in the central station, and code 20 responsive means associated with each remote device, all of the code responsive means associated with said devices being responsive to a code common to the associated group and also to an individual code to effect the operation 25 of said signal when the associated device is in said predetermined position and said code sending means is operated to transmit either of said codes.

6. The combination, in a supervisory system, a central station, a plurality of remote devices, a high frequency generator associated with each device having an energizing circuit, a pair of conductors extending from said central station to each of said generators, 30 means responsive to operation of a device to a predetermined position for closing said energizing circuit, thereby to cause said generator to supply high frequency current to said conductors, a time delay relay controlled 35 by the operation of said device for interrupting said circuit after a predetermined interval, means in the central station for sending coded impulses over said conductors, selective means responsive to said coded impulses for 40 closing said energizing circuit when the associated device is in said predetermined position, and an indicating device in said central station responsive to high frequency current 45 received from said conductors.

50 7. In a supervisory system, a plurality of devices, signal sending apparatus associated with each device and having an actuating circuit, means associated with each device for completing the actuating circuit of the associated signal sending apparatus when the device 55 is automatically operated to a certain position, means associated with each signal sending apparatus for interrupting its respective actuating circuit a predetermined 60 time interval after the automatic operation of the associated device, and remote controlled means for completing any of said actuating circuits without operating the associated device.

65 8. In a supervisory system, a plurality of

devices, a high frequency induction coil associated with each device and having an actuating circuit, means associated with each device for completing the associated actuating circuit in response to the operation of the device to a certain position, means associated with each device for interrupting the associated actuating circuit a predetermined time interval after the operation of the device to said certain position, and remote controlled 70 means for subsequently completing any of said actuating circuits when the associated device is in said certain position without operating the device.

9. In a supervisory system, a plurality of devices, each having a normal and an off-normal position, signal sending apparatus associated with each device and having an actuating circuit, means associated with each device for completing the associated actuating circuit when the device is operated to its off-normal position, means associated with each signal sending apparatus for opening its respective actuating circuit a predetermined time after the completion thereof, a normally closed switch associated with each signal sending apparatus, remote controlled means for completing each actuating circuit through the associated switch when the associated device is in its off-normal position, 95 remote controlled means for opening each switch, and means responsive to the operation of a device to its normal position for closing the associated switch.

10. In combination, a central station including an indicating device, a plurality of remote devices arranged in groups, each device being capable of assuming different positions, each group and each device in each group having an individual code, a signal circuit associated with each device, means associated with each group responsive to the code individual to the group to control all of said circuits, said means being responsive to the individual codes of each device to control the signal circuit of the respective device, means controlled by said signal circuit to operate said indicating device, and means associated with said remote device, for preventing operation of said indicating device 105 dependent upon the position of the respective remote device.

11. In combination, a central station including an indicating device, a plurality of remote devices arranged in groups, each device being capable of assuming different positions, each group and each device in each group having an individual code, a signal circuit associated with each device, means associated with each group responsive to the code individual to the group to control all of said signal circuits, said means being responsive to the individual codes of each device to control the signal circuit of the respective device, means controlled by said sig- 120 125 130

- nal circuit to operate said indicating device, and means associated with said remote device for preventing operation of said indicating device dependent upon the position 5 of the respective remote device, and additional means associated with each remote device for rendering said code responsive means unresponsive to control the corresponding signal circuit.
- 10 12. In a supervisory system, a plurality of devices each of which is capable of assuming either of two positions, a signal having an actuating circuit, a selector switch associated with each device and operable to 15 a certain position responsive to two or more codes, connections whereby said actuating circuit is controlled by said switches when in said certain positions thereby to cause operation of said signal, means for preventing 20 operation of the signal dependent upon the positions of the two-position devices, and means responsive to the operation of a selector switch to a different position to prevent operation of said signal when the selector 25 switch is subsequently operated to said certain position.

13. In a supervisory system, a plurality of devices each of which is capable of assuming either of two positions, a signal having 30 an actuating circuit, a selector switch associated with each device and operable to a certain position responsive to two or more codes, connections whereby said actuating circuit is controlled by said switches when 35 in said certain positions thereby to cause operation of said signal, means for preventing operation of the signal dependent upon the positions of the two-position devices, a relay associated with each selector switch 40 and having contacts connected to control said energizing circuit, means responsive to the operation of a selector to a predetermined different position for operating the associated relay to one position to control said actuating circuit and responsive to the operation 45 of the associated device to operate the relay to another position.

In witness whereof, I have hereunto set my hand this 17th day of September, 1928.

50 CLYDE E. STEWART.
